UNITED STATES PATENT OFFICE

CARL C. ROSSI, OF ERIE, PENNSYLVANIA

BRACKET

Application filed February 12, 1929. Serial No. 339,476.

This invention is designed to provide a convenient means of supporting walls in course of construction and for analogous uses. It is particularly desirable with relation to veneer walls. Such walls in the course of construction move out of alignment, either under the influence of frost, excessive heat, or in pointing the wall. The present device provides a support in which the wall can be definitely anchored to the frame of the building and thus preventing the bulging of the wall while the mortar is still soft. Features and details of the invention will appear from the specification and claims.

16 A preferred embodiment of the invention is illustrated in the accompanying drawings as follows:—

Fig. 1 shows a perspective view of a wall with the device in place.

20 Fig. 2 a section of a wall with a side elevation of the device.

Fig. 3 a perspective view of the supporting arm.

Fig. 4 a perspective view of one of the adjustable angle plates.

Fig. 5 a perspective view of the other of the angle plates.

1 marks the studding, 2 the sheeting of a veneer building, and 3 a wall in course of construction. A supporting arm 4 is provided with a longitudinal slot 5 along the arm. The arm is provided with a foot 6 which is preferably provided with a key-hole slot 7 and a slot 8 opening to the side of the arm. The arm is secured to the sheeting by a nail A. This nail is ordinarily driven so as to clamp the foot against the sheeting. If the space between the wall and the sheeting is sufficient a key-hole slot is preferably used and it can be loosened from the nail by driving upwardly on the foot, the space between the wall and the sheeting permitting the use of a hammer to drive the foot in this direction. If the space between the wall and the sheeting is too small for this purpose the slot 8 is preferably used and then the foot is released from the nail by driving it laterally in a horizontal direction.

An angle plate 9 has a downwardly extending portion and a base 10 which is ar-

ranged against the supporting arm 4. It has a longitudinal slot 11 corresponding to the slot 5. A second angle plate 12 has a downward extending portion and base 13. A screw 14 extends from the base 13 through the slots 11 and 5. A thumb nut 15 is provided by operating on the screw which when set up clamps the plates 9 and 12 on the supporting arm.

It will readily be seen that with this structure the angle plates may be adjusted relatively to each other to vary the distance between the downwardly projecting portions so as to accommodate different thicknesses of walls. The plates 9 and 12 may be adjusted outwardly, or inwardly on the arm by a movement of the screw along the slot 5 so as to adjust the supporting projections on the angle plates at the right distance from the support, as for instance, the sheeting to retain the wall in alignment.

While I have shown this in relation to a veneer wall it will be understood that the use of the device is not limited to this particular form of wall, or to retaining the specific structure shown.

What I claim as new is:—

1. In a bracket, the combination of a projecting arm; a foot on the arm; two angle plates mounted on the arm, each plate being slidably mounted on the arm and to each other; and means locking the plates together on the arm.

2. In a bracket, the combination of a projecting arm; a foot on the arm; two angle plates mounted on the arm, the arm and bases of the angle plates forming relatively adjustable members, two of said members being longitudinally slotted; and a clamping screw extending through the slots and secured to the third member clamping the bases and arm together, the slots permitting the adjustment of the plates to each other and to the arm.

3. In a bracket, the combination of a projecting arm; a foot on the arm having a nail slot, said slot permitting a lateral movement of the foot relatively to a securing nail to loosen the foot from engagement with the

head of the nail; and angle plates secured to the arm.

4. In a bracket, the combination of a projecting arm; a foot having a key-hole slot, the elongation of the slot extending vertically lengthwise of the foot and a second slot extending crosswise of the foot; and angle plates secured to the arm.
5. In a bracket, the combination of a projecting arm; a foot on the arm having a nail-slot, said slot permitting a lateral movement of the foot relatively to a securing nail to loosen the foot from engagement with the head of the nail; two angle plates mounted on the arm, each plate being adjustable to the arm and to each other.

In testimony whereof I have hereunto set my hand.

CARL C. ROSSI.
